US00D806817S

(12) **United States Design Patent** (10) Patent No.: **US D806,817 S**
(45) Date of Patent: ** Jan. 2, 2018

(54) **EXERCISING APPARATUS**

(71) Applicant: **KOMPAN A/S**, Odense Sø (DK)

(72) Inventors: **Nikolaj Maj Bentsen**, Vejle Ø (DK);
Martin Nørgaard Johansen, Skårup Fyn (DK)

(73) Assignee: **KOMPAN A/S**, Odense (DK)

(**) Term: **15 Years**

(21) Appl. No.: **35/500,802**

(22) Filed: **Mar. 1, 2016**

(80) **Hague Agreement Data**

Int. Filing Date: **Mar. 1, 2016**

Int. Reg. No.: **DM/089964**

Int. Reg. Date: **Mar. 1, 2016**

Int. Reg. Pub. Date: **Apr. 8, 2016**

(30) **Foreign Application Priority Data**

Sep. 2, 2015 (EM) 002764803

(51) **LOC (11) Cl.** **21-03**

(52) **U.S. Cl.**

USPC **D21/826**

(58) **Field of Classification Search**

USPC D21/826, 814

CPC A63B 9/00

See application file for complete search history.
